UNITED STATES PATENT OFFICE.

WARREN Z. WOODSTOCK, OF CARTHAGE, MISSOURI, ASSIGNOR OF ONE-HALF
TO ALFRED A. ULMAN, OF BAY ST. LOUIS, MISSISSIPPI.

SHEDDING MECHANISM FOR LOOMS.

SPECIFICATION forming part of Letters Patent No. 360,398, dated March 29, 1887.

Application filed July 16, 1885. Serial No. 171,741. (No model.)

To all whom it may concern:

Be it known that I, WARREN Z. WOODSTOCK, a citizen of the United States, residing at Carthage, in the county of Jasper and State of Missouri, have invented certain new and useful Improvements in Shedding Mechanism for Looms; and I do hereby declare the following to be a full, clear, and exact description of the invention, such as will enable others skilled in the art to which it appertains to make and use the same.

My invention relates to shedding mechanism for looms; and its object is to provide a cheap, simple, and durable mechanism for producing positive and accurate upward and downward motion of the harness-frames of a loom. This object I attain by the means illustrated in the accompanying drawings, forming a part of this specification, in which—

Figure 1 is a view, in rear elevation, of a loom having the invention applied thereto. Fig. 2 is a detail showing the supports and guides for the jacks. Fig. 3 is a detail showing one of the jacks with its attached frame for holding the harness-frame. Fig. 4 shows one of the spring-catches detached. Fig. 5 is a detail showing the cam-shaft detached. Fig. 6 shows one of the cams detached. Fig. 7 is a section of the devices longitudinally of the cam-shaft, showing the first jack raised and all others down.

Similar letters of reference indicate corresponding parts in the several figures.

A is a frame for guiding the jacks. It is composed of pieces *a*, mounted upon cross-pieces *b*, which are supported upon posts *B*. The pieces *a* are provided with lugs *a*³ *a*³ at each end, to prevent them from working endwise. To hold them down firmly, a piece, *b*², is secured by bolts or other suitable means at each end, so that by removing it the pieces *a* may be taken out. Said pieces are held the desired distance apart by means of lugs *a*² *a*² and *a*⁴ *a*⁴, &c., to form the slots *a*⁵ *a*⁵ for receiving the jacks and for forming a support and guide for the upper ends of the same.

C are suitable boxings for the cam-shaft, which is placed at right angles to the slots *a*⁵.

D is a jack having a slot, *d*, for receiving the hub of its operating-cam *F* and holding the lower end of the jack steady. Above this

slot is a pin or projection, *d*¹, for receiving a non-frictional roller, *d*², which works in the groove *G* of the cam, so as to be raised and lowered as the cam revolves, thus raising and lowering the jack.

E is a frame, having uprights *e*, provided with longitudinal slots *e*¹ for receiving the harness-frame. The head-piece *e*² of frame E is provided with spring-catches *O*, which have a slanting-head, *o*, to let the harness-frame slip down, and a straight edge, *o*¹, to catch and hold the said harness-frame down. This frame E may be firmly secured to, but is preferably formed a part of, the jack.

F is a cam of any desired size and shape, having a hub, *f*², and an opening, *f*, which is provided with a key seat or groove, *f*¹. The key-seat may be made at any desired angle with the axis of the groove *G*, as hereinafter set forth.

G is a groove, made in the side of each of the cams, of any desired size and shape, preferably elliptical in shape.

H is a cam-shaft, having suitable journals, *h* *h*¹, and a beveled gear-wheel, K, to engage a beveled pinion, N, which is upon the lower or picking shaft, M. Said shaft H has a rib, *h*², to enter the grooves *f*¹ of the cams, to hold them firmly in place and cause them to revolve with the shaft. It is also provided with threads and a nut, R, to tighten the cams F against a pin or key, *h*³. The key-seats *f*¹ may be placed at any desired angle with the line of the major axis of the groove *G*, which receives the non-frictional roller for raising and lowering the jack. Thus, in the ordinary loom having five jacks, the key-seats are placed, the first at any given point and the other four varying one-fifth of the circumference, or seventy-two degrees, from each other and from the first as indicated by the dotted lines *f*⁴, *f*⁵, *f*⁶, and *f*⁷, and the groove *f*¹ in Fig. 6.

In the illustration, Fig. 7, the first jack, D', is up and all others down. The jacks and cams being alternated upon the shaft H, and the cams having the grooves one-fifth of a circle apart, and being five in number, they will raise the jacks thus: the first, third, fifth, second, fourth, and then first again, &c. The motion is made positive, both up and down, by the roller *d*², which rests against one side of

the groove in raising the jack, and against the other in descending, thus making a perfect motion. The cams and jacks may be easily removed and replaced by unkeying the pieces 5 b^3 and loosening the nut R, which lets the plate or large washer S slip back, so that the key or pin h^3 may be drawn. The removal of this pin allows the cams and jacks to be removed alternately, so that they may be repaired or 10 replaced in a different order. The major axis of the groove G in the cam may be increased in proportion to the distance from the front of the loom, so that the shuttle may have the same space between the warp-threads at each 15 pick. The shaft H may be made to receive any desired number of cams and jacks.

Having thus described my invention, what I claim as new, and desire to secure by Letters Patent, is—

20 1. A frame composed of posts B, cross-pieces $b\ b^1\ b^2$ and pieces $a\ a$, provided with lugs a^3 , a^2 , and a^4 , forming slots a^5 , &c., substantially as shown and described.

2. The combination, with shaft H, having a rib, h^2 , of gear-wheels K N, lower pick-shaft, 25 M, cams F, provided with grooves G and key-seats f' , jacks D, provided with slots d and non-frictional rollers d^2 , and frames A E, the latter having springs O, substantially as set forth.

3. The combination of a frame, A, having detachable pieces a , provided with lugs $a^2\ a^3\ a^4$, and means for securing said pieces a in position, with jacks D, having slots d and non-frictional, rollers d^2 , frames E, having arms e , 35 with grooves e' , springs O, cams F, provided with grooves G and projecting hubs f^2 , a shaft, H, lower pick-shaft, M, and gear-wheels K N, all substantially as and for the purpose set forth.

In testimony whereof I affix my signature in presence of two witnesses.

WARREN Z. WOODSTOCK.
